APPARATUS FOR REMOVING ICICLES FROM
THE EAVES OF BUILDINGS

Benjamin F. Liston, Garrettsville, Ohio

Application April 21, 1947; Serial No. 742,980

4 Claims. (Cl. 108—1)

1

This invention relates to apparatus for eliminating the hazard of falling icicles by dislodging them mechanically, particularly from locations above doors or the like through which people or vehicles pass.

Under certain weather conditions, i. e., rainfall with freezing temperature, icicles of substantial size and weight are formed on the eaves or other overhanging projections of buildings. So long as the temperature is below freezing the icicles are not likely to become detached unless the wind is high but on the commencement of a thaw, they are apt to fall at any time and may thus constitute a serious danger to those walking or working below. In fact, fatal accidents have occurred as a result of this hazard.

I have invented an apparatus for forcibly removing icicles from the eaves of a building before they begin to fall as a result of a thaw. The apparatus is intended for installation over doorways or other locations where people are coming and going. It comprises a rotatable sweep member including a horizontal shaft journaled on the building adjacent the eaves, with striker means adapted to knock down icicles depending therefrom, and means for rotating the shaft at will. The striker means is preferably an elongated vane extending laterally from the shaft, so that its outer edge passes in close proximity to the eave on rotation of the shaft.

A complete understanding of the invention may be obtained from the following detailed description which refers to the accompanying drawings illustrating the present preferred embodiment. In the drawings,

Figure 1 is a partial section, somewhat diagrammatic, through a building adjacent an eave thereof showing the invention in end elevation;

Figure 2 is a side elevation; and

Figure 3 is a plan view.

Referring in detail to the drawings, the invention is intended for installation on a building such as that indicated generally at 10 which may be of any type. As an example, I have shown an industrial building including spaced columns 11 with sheathing girts 12 extending therebetween to which corrugated metal siding sheets 13 are secured, and a roof 14. The icicle remover of my invention, indicated generally at 15, comprises a sweep member including a shaft 16 extending alongside the building below the eave and an elongated vane 17 extending laterally therefrom and of such width that its outer edge passes in close proximity to the edge of the eave on rotation of the shaft. The shaft is journaled

2

in suitable bearings carried by arms 18. These arms are adjustably mounted on brackets 19 secured to the columns 11.

The sweep member is provided with means for 5 rotating it such as a sheave 20 secured to the shaft having an endless loop of chain or rope 21 trained therearound and depending therefrom to a level at which it can easily be seized by an operator. The sheave may be located in any convenient point along the shaft 16. In the embodiment illustrated, it is disposed substantially centrally between two lengths of hollow shaft 16a and 16b and has a stub shaft 23 extending therethrough entering the ends of the hollow shaft sections and bolted thereto as at 22. Auxiliary supporting arms 24 provide bearings for the stub shaft 23 and are adjustably mounted on brackets 25 secured to the sheathing girts.

It will be apparent that when the shaft 16 is 20 rotated as by pulling on the one side of the chain loop 21, the vane 17 will sweep past the edge of the roof and dislodge any icicles depending therefrom as indicated at 26. The vane 17 is preferably curved as shown in Figure 1 to impart a slight springiness and may be slotted transversely as at 27 to clear the supporting brackets, although it is only necessary to rotate the vane through a relatively small angle to effect complete dislodgment of all depending icicles.

30 It will be understood that the apparatus, when installed above a doorway or entrance, may be operated by one standing inside the building adjacent the entrance with perfect safety since the sweep member may be turned in such direction as to cause the icicles when detached to fall away from the building wall.

The invention has numerous advantages in addition to the fact that it eliminates the safety hazard presented by the fall of icicles from building eaves. The apparatus is simple and inexpensive and may be easily operated to accomplish its intended object. When once installed, the apparatus is out of the way and takes up no useful space inside the building. It is, nevertheless, always ready for use without any special care or maintenance. Several units such as shown in the drawings may be coupled together end-to-end for wide openings and operated as a single device.

50 Although I have illustrated and described but a preferred embodiment of the invention, it will be apparent that changes in the details of the construction disclosed may be made without departing from the spirit of the invention or the scope of the appended claims.

I claim:

1. An icicle breaker for an eave projecting beyond a wall of a building and having a laterally extending edge, comprising spaced brackets mounted on the building, a shaft mounted on said brackets, said shaft being spaced from the edge of the eave below said edge and inwardly of said edge toward the wall, and a vane mounted on the shaft and having an edge adapted to swing closely past the edge of the eave when the vane is rotated.

2. An icicle breaker for an eave projecting beyond the wall of a building and having a laterally extending edge, comprising spaced brackets mounted on the building, a shaft rotatably mounted on said brackets, said shaft being spaced from the edge of the eave below said edge and inwardly of said edge toward the wall, a vane rigidly mounted on the shaft and having an edge adapted to swing closely past the edge of the eave when the shaft is rotated, and means to rotate the shaft.

3. An icicle breaker for an eave projecting beyond a wall of a building and having a horizontally extending edge, comprising spaced brackets mounted on the building, a horizontal shaft rotatably mounted on said brackets, said shaft being spaced from the edge of the eave below said edge and inwardly of said edge toward the wall, a vane rigidly mounted on the shaft and having an outer edge adapted to swing closely past the edge of the eave when the shaft is rotated, said vane being hooked so that the por-

tion of the vane adjacent its outer edge lies in a substantially horizontal plane as the vane swings past the edge of the eave, and means to rotate the shaft.

5. An icicle breaker for an eave projecting beyond a wall of a building and having a horizontally extending edge, comprising spaced brackets mounted on the building, a horizontal shaft rotatably mounted on said brackets, said shaft being spaced from the edge of the eave below said edge and inwardly of said edge toward the wall, a vane rigidly mounted on the shaft and having an outer edge adapted to swing closely past the edge of the eave when the shaft is rotated, said vane being hooked so that the portion of the vane adjacent its outer edge lies in a substantially horizontal plane as the vane swings past the edge of the eave, and means to rotate the shaft comprising a sheave rigidly mounted on the shaft and a chain over the sheave and hanging therebelow.
